HOLDER FOR THERMIONIC VALVES AND
OTHER ELECTRICAL DEVICESGeorge Wagstaff, Long Eaton, England, assignor
to United-Carr Fastener Corporation, Cam-
bridge, Mass.Application February 1, 1945, Serial No. 575,718
In Great Britain April 27, 1944

5 Claims. (Cl. 174—35)

1

The present invention relates to holders for thermionic valves, electrical coil units and other electrical devices and saddle or like means for securing them to a panel or support.

According to the present invention a saddle or like means for mounting the holder on a supporting panel is provided with integral projecting lugs adapted to engage in bayonet or other slots in a metal screening can to secure the can to the saddle over the valve or other electrical device.

To enable the invention to be fully understood it will now be described with reference to the accompanying drawings, in which:

Fig. 1 is a side elevation partly in section of one embodiment of the invention on the line 1—1 of Fig. 2.

Fig. 2 is a plan view of the saddle and holder shown in Fig. 1, and

Fig. 3 is a plan view of the lower plate of the saddle.

As shown in the accompanying drawings 1 indicates a valve holder having a projecting flange 2. The contacts, normally mounted in the holder, are omitted from the drawings for the sake of clarity. The saddle adapted to secure the holder to the panel 3 comprises a pair of metal plates 4, 5 each having lateral extensions 6 apertured to receive bolts or the like 7 to secure the saddle to the panel 3.

The upper saddle plate 4 is formed with a central aperture through which the front face of the holder projects. Rim portions 8 extend inwardly of this aperture and overlap the upper face of the flange 2. The other plate 5 is formed with a generally rectangular aperture having four side edges 9 which overlap and extend beneath the flange 2. At each corner of the aperture integral lugs are provided comprising a portion 10 extending at right angles to the plane of the plate 5 and an arm 11 which is bent outwardly from the position shown in dotted lines in Fig. 3 to that shown in full lines on the various figures after two plates have been assembled with the holder. The arm 11 is adapted to engage in the bayonet slot 12 formed in the cylindrical side wall of a metal screening can 13 which is normally fitted over the valve or coil unit which would be mounted in the holder. The arm 11 also serves to prevent separation of the plates 4, 5 when it is bent into the full line position and accordingly the holder and saddle are retained in assembly and may be handled as a unit.

I claim:

1. A saddle or like member for mounting a

2

holder for an electrical device on a supporting panel, said saddle comprising a pair of apertured plates in superposed relation, one of said plates having an upstanding portion providing a lug element extending in a plane generally parallel to said plate for engaging one side of said holder, and the other of said plates having means for engagement with a side of said holder opposite said one side and having an integral upstanding element providing an arm element adjacent its free end for fastener engagement with a shielding device adapted to be secured to said saddle in position to screen said device.

2. A saddle or like member for mounting a flanged holder for an electrical device on a supporting panel and for securing a shielding device for screening said electrical device, said saddle member comprising a pair of superposed plates, the upper of said plates having an aperture, an upstanding portion adjacent said aperture, and means on said upstanding portion for engagement with the upper face of the flange of said holder, and the lower of said plates having an aperture underlying said aperture of said upper plate, a marginal surface adjacent its aperture for engagement with the lower face of said flange, and an upstanding element extending through said aperture of said upper plate and having adjacent its free end an arm element overlying said upstanding portion and providing means for fastener engagement with said shielding device.

3. In the combination comprising an apertured support, a holder having a body disposed in the aperture of said support and a peripheral flange having an upper and a lower face, an electrical device mounted on said holder, and a shielding device for screening said electrical device, a saddle or like member for mounting said holder to said support and for mounting said shielding device in fixed relation to said electrical device, said saddle member comprising a pair of superposed plates having superposed lateral extensions providing means for attachment to said support, the upper of said plates having an aperture, an upstanding wall portion surrounding said aperture, and a lug element extending from the top of said wall portion inward over said aperture substantially parallel said plate for engagement with said upper face of said flange, and said lower plate having a second aperture underlying said aperture of said upper plate, a marginal surface adjacent said second aperture for engagement with said lower face of said flange, and an upstanding integral element extending from the edge of said second aperture adjacent the inner surface of

4

said wall portion and having adjacent its free end an arm element overlying said wall portion for fastener engagement with said shielding device.

5. A saddle or like member for mounting a flanged holder for an electrical device on a supporting panel and for securing a shielding device for screening said electrical device, said saddle comprising a pair of superposed plates having superposed lateral extensions with means for attachment to a supporting panel, the upper of said plates having an aperture and an upstanding wall portion surrounding said aperture, and lug elements extending inward from the top of said wall portion in a plane substantially parallel said plate for engagement with the upper face of the flange of said holder, and the lower of said plates having an aperture underlying the aperture of said upper plate, marginal surfaces adjacent its aperture underlying said lug elements for engagement with the lower face of the flange of said holder, and integral upstanding elements disposed adjacent the inner surface of said upstanding wall portion intermediate said lug elements and provided with arm elements adjacent their free ends extending over said upstanding wall portion for fastener engagement with said shielding device.

6. A saddle or like member for mounting a flanged holder for an electrical device on a supporting panel and for securing a shielding device for screening said electrical device, said saddle comprising a pair of superposed plates, the upper
